UNITED STATES PATENT OFFICE.

ALBERT KRAUTH, OF HAMILTON, OHIO; FRITZ G. DIESBACH ADMINISTRATOR OF SAID
ALBERT KRAUTH, DECEASED.

MANIFOLDING-MACHINE.

1,333,082.

Specification of Letters Patent.

Patented Mar. 9, 1920.

Application filed May 20, 1916. Serial No. 98,733.

To all whom it may concern:

Be it known that I, ALBERT KRAUTH, a citizen of the United States, residing at Hamilton, in the county of Butler and State 5 of Ohio, have invented a new and useful Manifolding-Machine, of which the following specification is a full disclosure.

My invention relates to manifolding machines for autographic registers in which 10 one or a plural number of webs of paper usually comprising preprinted forms as bills of lading, sales slips and the like are supported, and in a superposed arrangement for manifolding, fed over a writing-table, 15 for exposure within a margin frame area and to be withdrawn from the machine and severed as to their form lengths. The paper used in the machine has apertures or perforations alined longitudinally in a spaced 20 relation, the degrees of spacing representing or corresponding to the measured sheet or form lengths and are also provided in pairs or plural number alined cross-wise of the strip. The apertures are utilized as indexes 25 for strip coöperation with intercepting devices arranged to engage through the apertures when brought into register therewith automatically determining the length of 30 paper withdrawal. The intercepting devices when engaged through the apertures are also utilized for feeding or withdrawing the strip from the machine sufficiently for manually grasping to be followed by a manual withdrawal until arrested by the intercepting 35 devices. The intercepting devices when operating as feeding means receive their motion from the crank handle mounted external of the machine. The crank handle rotating cam devices which operate and control the intercepting devices for moving the 40 same in a forward or paper feeding direction when engaged with the paper, releasing their paper engagement for a restoration of the parts for a subsequent operation leaving 45 the intercepting elements as detents free to engage through the apertures in the paper when brought into alinement therewith. The mechanism provides for a quick and 50 convenient manipulation, without careful observation in extracting or withdrawing the paper in determined or measured sheet lengths and leave a successive portion of the web appropriately over the writing table for its proper exposure within the margin 55 frame, restrained against displacement;

alining and registering the webs when several are employed for manifolding purposes, with respect to each other and to the parts of the machine, and a withdrawn portion of the paper can be severed across a tearing 60 blade without disturbing that portion of the web over the writing table.

The invention therefore, has as an object to provide a member movable in a direction to and fro corresponding to the longitudinal 65 feeding or withdrawing direction of motion of the paper over the writing table of the machine, said member carrying fingers or detents yieldingly urged to move transversely through apertures in the paper when 70 the apertures are brought into registry therewith, as a stop or barrier against paper withdrawal or movement over the writing table, alining and registering the webs with relation to each other and further for providing a connection or engagement with the paper for withdrawing the same when the detents are moved in a paper feeding direction or transversely to their aperture engaging motion. And, in providing means for 75 controlling and operating said detents.

The various features and objects of the invention will be more fully revealed in the description of the accompanying drawing, illustrating a preferred embodiment of the 80 invention, forming a part of the specification, and in the drawings like characters of reference denote corresponding parts throughout the several views;

Figure 1 represents a central vertical section of a manifolding device contained in my invention and improvements;

Fig. 2 is a side elevation of an end portion of the machine;

Fig. 3 is a vertical section of such end 95 portion of the machine shown in Fig. 2, but taken on a different line from a similar portion of the machine to that shown in Fig. 1;

Fig. 4 is an end elevation of the machine;

Fig. 5 is a top plan view of that portion 100 of the machine shown in Fig. 2 with parts broken away to expose hidden parts;

Fig. 6 is a section on line 6—6, Fig. 1;

Fig. 7 is a detail plan view of the paper intercepting and feeding devices;

Fig. 8 is a plan view of a portion of the web of the paper used in the machine illustrating the apertured spacing.

As the invention has particular utility in manifolding machines or autographic regis- 110

ters the description will be confined to such class of machines and to the simplest form or type of machine in that class. The machines usually are loaded with several webs 5 of paper arranged in a superposed relation over the writing table with a sheet of ink or carbon paper interposed between the web for manifolding; although some instances of use may only require a single web and the 10 operation of the machine is equally as efficient, either with one or a plural number of webs. In operating upon a plural number of webs with each comprising, say, duplicate printed forms, in which it is essential 15 that the forms be alined and register one over the other for accurate manifolding results, the detent or intercepting means when entering the apertures in the paper function to correct any slight inaccuracies in the 20 registration between the web portions over the writing table. As heretofore stated and as shown in Fig. 8, the paper longitudinally is provided with alined apertures definitely spaced, the degrees of spacing 25 usually coordinate to a measured or determined sheet or form length and disposed within divisional blank spacing separating the forms successively. The paper is apertured or perforated at the time of printing 30 and thus the apertures are very accurately located with respect to the printing and as the intercepting means or detents function with reference to the length of strip between the perforation and also in relation 35 to the web position and registry over the writing table, the paper is always brought and arrested for a proper form exposure defined as to its area by the margin frame over the writing table.

40 Referring to the drawings, 1 and 2 indicate a pair of side frames, which may be of sectional form, forming a carrier, one section hingedly mounted upon a second, with the opposite forward companion sections of both frames connected as a unit and adapted to be swung for convenient access into the interior of the casing. The side frames, oppositely, are provided with supports for journaling the webs of paper 45 under a proper degree of tension. A writing table 3 is secured upon and supported between the side frames over which the paper is withdrawn and upon which the paper is supported. A margin frame 4 mounted on one of the side frames extends over the writing table, said margin frame being adapted to be locked in its closed position. The writing table is mounted between the side frames so that its upper surface, 50 upon which the webs are supported, lies slightly below the upper edges of the side frames, so that the side frames and table provide a channel for the paper, of a width approximately equal to that of the web, 55 freely guiding the paper as it is withdrawn

from the machine. The parts of the machine just described are common to machines of this class and thus may represent a commercial type of construction.

The forward end of the margin frame is 70 bent acutely upward to form a flange 5, reinforcing such margin frame end and providing an inclined support for the tearing blade 6, which is fixed to the flange. The cutting edge of blade is at an elevation 75 slightly above the writing table to clear the paper and not interfere with the paper withdrawal. The margin frame as above stated is suitably locked or maintained rigid which is necessary when tearing the paper, in an 80 upward action, across the edge of a knife.

A swinging carrier 7, in the form of a plate, is hingedly mounted upon a rod 8, said rod connecting with the side frames and as shown the rod provides an axis upon 85 which the forward side frame sections swing. The fulcrum end of the carrier is looped around the rod and slotted intermediately, as at 9, through which a pin, secured to the rod, projects. The pin qualifies as a stop to 90 limit the swinging motion of the carrier, preferably at the outward limit of carrier motion. A spring 11, coiled around the rod 8, has one of its ends fixed to the rod and its opposite end to the carrier providing the 95 proper tension for automatically returning the carrier to its normal position and maintains the carrier yieldingly against its cam actuator. A detent carrying plate 10 is slidably mounted upon the carrier 7 by screws 100 12 engaged into the carrier plate 7 each through an elongated slot in the plate 10. (See Figs. 6 and 7.) The plate 10 sliding or reciprocating upon the plate in a plane parallel to said plate 7 is yieldingly urged 105 upwardly by the spring 13—13, fixed to the carrier plate 7 and detent plate 10. The plate 10 is provided with two pins or detents 14—14 projecting from its upper end and relatively spaced, in degrees corresponding to the spacing of the crosswise alined apertures or perforations in the paper. Each detent is adapted in an upward motion to engage through a respective oblong slot 15 in the writing table 3 and through a 110 registering oblong slot 16 in the margin frame 4. The detents for a paper feeding or withdrawing operation are depressed or retracted to bring them below the table plane out of the path of the traveling paper, such 115 operation in the instance herein taking place after the paper has been withdrawn slightly or projected beyond the knife edge of the tearing blade, which places the paper apertures beyond a registering reach of the detents in their normal position, and in their 120 normal position the detents are free to engage against the non-perforated under surface of the paper and automatically enter or snap through a succeeding set of apertures 130

when brought into registry therewith. The 5 detents in entering the apertures in the paper exert a drawing influence on the several webs, if their apertures are not in absolute register with the detents, alining the webs with respect to each other and machine parts and when the detents are engaged through the paper confines the paper against displacement in any direction over the writing 10 table and also holds the paper against being withdrawn when severing a withdrawn portion across the tearing blade. With a stationary tearing blade it will be observed that after a withdrawn portion of 15 the paper has been severed, that the end of the portion of paper within the machine is flush with the knife edge and impossible to grasp for a subsequent withdrawal. Imparting a forward motion to the detents 20 when engaged through the paper, the paper is drawn therewith bringing its end beyond the tearing blade. Such detent motion results from swinging the carrier forward a slight distance sufficient to extract the paper 25 for manual grasping. To swing the carrier 7 I provide a shaft 17 extended to journal in the side frames, with one end thereof projecting externally beyond one of the side frames to receive a handle 18 which is fixed 30 to the shaft. (See Figs. 5 and 6.) A cam 19 of a particular outline is fixed upon the shaft 17, (see Fig. 3), the periphery of the cam engaging the carrier moving the carrier forward in each revolution. A portion of 35 the cam surface as at 20, is concentric with its axis and when engaging with the carrier does not influence the carrier, providing a dormant period for the carrier in its outermost position during which the detents are 40 retracted or disengaged from the paper and retained in such retracted position until the parts are returned to their normal position. The cam 19 engages the plate 7 through a slot 22 in the plate 10 and the slot provides a 45 shoulder or abutment in the plate 10 adapted to be engaged by the cam for depressing the detents. The plate 10 at such cam engaging shoulder is provided with a projecting cross-lug 23 as a shoulder extension, 50 preventing the detents from being released by the cam or before the carrier has been returned and locked in its normal position. The releasing moment of the detent carrying plate in the construction shown is after 55 the carrier plate has been restored and locked in its normal position bringing the detents at right angles to the table, preventing them from interfering with the carrier return through possible engagement with 60 the traveling paper. A latch member 24 is supported and swiveled upon the cross rod 25 and as a bell crank, provides two arms projecting at right angles to each other, one as a latch arm projecting to engage through 65 a slot 26 in the carrier plate, and notched to provide a shoulder for engaging said plate 7, locking said plate in its normal position, and of an extended length beyond the shoulder to confine the arm within the notch in the carrier plate at the forward limit of 70 carrier motion. The latch arm is released by a cam finger 27 fixed upon the shaft 17 engaging the latch arm 28, and in a timed relation with respect to the cam 19 in each shaft revolution to raise the latch arm from 75 its engagement with the carrier plate, before the carrier plate moves outwardly for a paper feeding or withdrawing operation. The latch moves by gravity into its carrier locking position after the carrier has been 80 restored to its normal position. With the carrier normally locked against motion, the detents likewise are held rigid against counter motion or motion in an arc or transverse to their paper intercepting motion so 85 as not to be influenced by the motion of the paper as it is being withdrawn which would disturb their paper intercepting position. Motion stop devices are provided for preventing reverse motion of the shaft 17, said 90 devices comprising a flexible pawl blade 30, fixed to the side frame of the machine and projected to engage with the ratchet teeth formed on the end of the crank handle hub 31. The shank portion of the crank handle 95 is flexible and tensioned inwardly toward the side frame so as to engage with a rigid stop block 32 projecting from the side frame, (see Fig. 2), limiting the free rotation of the crank handle to a single revolution 100 and requiring the shank to be flexed outwardly, to free it from the stop for a subsequent cycle. Various forms of motion stop devices, well known in the art, may be employed in lieu of that shown for continuous direction cycle operations and so contemplated within the concept of this invention. 105

Having thus described my invention I claim:—

1. A device of the class described comprising a casing, a writing table mounted within said frame for supporting a web, the web having apertures spaced longitudinally, a swinging member having a depressible detent movable thereon for engaging a registering aperture in the web, and withhold the web against advancement over said writing table and means engaging said member and detent for swinging said member and for depressing said detent at the end of a paper advancing stroke of said member. 115
2. A device of the class described, comprising a casing having a web supporting writing table, the web having apertures in spaced relation longitudinally, an oscillating member mounted within the casing below the table, having a yielding reciprocable detent for engaging transversely through a 120
3. A device of the class described, comprising a casing having a web supporting writing table, the web having apertures in spaced relation longitudinally, an oscillating member mounted within the casing below the table, having a yielding reciprocable detent for engaging transversely through a 125
4. A device of the class described, comprising a casing having a web supporting writing table, the web having apertures in spaced relation longitudinally, an oscillating member mounted within the casing below the table, having a yielding reciprocable detent for engaging transversely through a 130

- registering aperture and withholding the web against advancement over the writing table and advance the web therewith in a forward oscillating motion of said member.
- 5 3. A device of the class described, comprising a casing having a web supporting writing table, a cross member bridging over the writing table and the web upon the writing table, the web having apertures spaced 70 longitudinally, a pivoted detent supporting member, a detent member slideable radially upon said supporting member and swinging as a unit therewith, said detent yieldingly urged toward the web to engage an aperture 10 in the table and in the cross member and registering apertures in the web, and means engaging said detent supporting member and detent, operating to swing said member with the detent engaged with the web 15 and advancing the web in a forward stroke of the member and for depressing said detent at the end of an advancing stroke of said member for releasing its web engagement.
- 20 4. A device of the class described, comprising a casing having a web supporting writing table, a pivoted member having a depressible detent normally engaging the web upon the table to prevent its being drawn 25 out, and means for rocking said member and through the detent web engagement draw the web end beyond the table to be grasped by hand, and sequentially depressing said detent releasing the web.
- 25 5. A device of the class described comprising a casing having a table for supporting a web of paper, a hinged member normally locked in a position at right angles to and beneath the table, a detent member 30 mounted upon said hinged member arranged to engage registering apertures through the web of paper upon the table, the web having apertures spaced longitudinally and laterally of the web, a latch arm for engaging 35 with and locking said hinged member against forward motion, a rotating cam for engaging said hinged member to swing the same forward and engaging said detent at the end of a swinging stroke for depressing 40 the same and releasing the web, and a second cam for operating said latch member for releasing said hinged member.
- 45 6. In a manifolding machine comprising a suitable frame work from which strips of paper are withdrawn, the combination with a platen over which said paper passes, of vertically disposed depressible pins hingedly mounted and located adjacent the forward end of said platen that engage said 50 paper, and means for swinging said pins forward and means for moving the same downward below the plane of said platen.
- 55 7. A manifolding machine comprising a suitable frame work inclosing a strip of paper having a longitudinally disposed series

of alining perforations, in combination with a device situated at the front end of said frame-work and arranged to enter said perforations, *seriatim*, and means for moving said device forward and means for withdrawing it from said perforations, whereby said paper initially advanced a distance to a position where it can be grasped by the fingers.

8. A manifolding machine comprising a suitable frame-work inclosing a strip of paper having a longitudinally disposed series of alining perforations, in combination with a device hingedly mounted and provided with depressible pins arranged to enter said perforations, and means for swinging said device forward and means for moving the pins downward withdrawing the pins from the perforations, whereby said paper is advanced to a position where it can be grasped by the fingers.

9. A manifolding machine comprising a suitable frame work inclosing a strip of paper having a longitudinally disposed series of alining perforations, in combination with a device hingedly mounted and provided with depressible pins arranged to enter said perforations, means for swinging said device forward and means for moving the pins downward withdrawing the pins from the perforations, whereby said paper is advanced to a position where it can be grasped by the fingers, and means for locking said device in its normal position controlled by said first-named means.

10. In a manifolding machine, a frame inclosing a strip of paper, the strip having a longitudinally disposed series of alining perforations, a spring tensioned device hingedly mounted having depressible pins arranged to enter said perforations *seriatim*, a rotary cam having faces for swinging said device and depressing the pins at the end of their swinging motion and permitting the return of said parts with the pins depressed.

11. In a manifolding machine, a frame inclosing a strip of paper, the strip having a longitudinally disposed series of alining perforations, a table within the frame over which the strip of paper is drawn, a member hingedly mounted within the frame and beneath and adjacent one end of the table and having depressible pins arranged to enter said perforations *seriatim*, means for swinging said member forward with the pin engaged with the strip, and means for depressing said pins at the end of the forward stroke of said member and holding the same depressed on the return of said member.

12. In a manifolding machine, a frame inclosing a strip of paper, the strip having a longitudinally disposed series of alining perforations, a table within the frame over which the strip of paper is drawn, a yielding oscillating member having depressible

pins arranged to enter said perforations through the paper when in registry therewith, and means for swinging said member to advance the paper upon the table.

- 5 13. In a manifolding machine, a frame enclosing a strip of paper, the strip having a longitudinally disposed series of alining perforations, a table within the frame over which the strip of paper is drawn, depressible pins arranged to enter said perforations, *se-riatim*, means for swinging the pins in a direction for advancing the paper upon the table when engaged therewith, means for depressing said pins below the table to free the 10 paper and for holding said pins depressed during a non-paper advancing return stroke.
- 15 14. In a manifolding machine, a frame enclosing a strip of paper, the strip having a longitudinally disposed series of alining 20 perforation, a table within the frame over which the strip is drawn, a margin frame

above the table having a stationary tearing blade across its forward end, depressible pins, each respectively engaging through a longitudinal slot in the forward end of the 25 table and margin frame, and mounted to swing forward for advancing the strip when the pins are engaged through perforations in the strip, means for swinging said pins to advance the strip, and means for depressing said pins at the end of a strip advancing stroke to release the paper and for holding the pins depressed during a return swinging stroke.

In witness whereof, I hereunto subscribe 35 my name, as attested by the two subscribing witnesses.

ALBERT KRAUTH.
